(57) **CLAIM**

The ornamental design for a movable portable device holder, as shown and described.

DESCRIPTION

FIG. 1 is a perspective view of a movable portable device holder attached to a portable device protective cover in a first position, showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of the movable portable device holder of FIG. 1, attached to a portable device protective cover in a second position;

FIG. 9 is a perspective view of the movable portable device holder of FIG. 1 in an alternative environment, attached to a portable device protective cover in the first position; and, FIG. 10 is a perspective view of the movable portable device holder of FIG. 1 in the alternative environment of FIG. 9, attached to a portable device protective cover in the second position.

The broken lines in FIGS. 1-10 depict portions of the movable portable device holder and portable device protective cover that represent environment and form no part of the claimed design.

1 Claim, 8 Drawing Sheets
